E. W. Bradford,

UNITED STATES PATENT OFFICE

GEORGE E. KRAUSE, OF INDIANAPOLIS, INDIANA.

BED-LOUNGE.

SPECIFICATION forming part of Letters Patent No. 325,344, dated September 1, 1885.

Application filed March 17, 1885. (No model.)

To all whom it may concern:

Be it known that I, GEORGE E. KRAUSE, of the city of Indianapolis, county of Marion, and State of Indiana, have invented certain new 5 and useful Improvements in Bed-Lounges, of which the following is a specification.

My said invention consists in various improvements in the construction of bed-lounges, whereby a convenient and desirable lounge is 10 provided, as will be hereinafter more fully described.

Referring to the accompanying drawings, which are made a part hereof, and on which similar letters of reference indicate similar 15 parts, Figure 1 is a perspective view of a bed-lounge embodying my said invention; Fig. 2, a longitudinal vertical section of the same in open position, looking to the left from the dotted line 2 2 in Fig. 3; Fig. 3, a transverse vertical section, looking to the right from the dotted line 3 3 of Fig. 2; Fig. 4, a view looking 20 to the left from the dotted line 4 4 in Fig. 3, showing a portion of the side in elevation; Fig. 5, a detail sectional view, looking to the 25 right from the dotted line 5 5 in Fig. 4, and Fig. 6 a horizontal sectional view, looking downwardly from the dotted line 6 6 in Fig. 4.

In said drawings the portions marked A represent the frame of the main section of the 30 lounge; B, the frame of the hinged section; C, a receptacle formed under the bed of the main section; D, said bed, and E hinged legs attached to and adapted to support the outer edge of said hinged section.

The frames A and B are of any suitable or 35 usual construction, the frame B having the lounge-upholstering and bed formed therein, and being hinged to the frame A at the front side of the lounge, as is usual.

The receptacle C consists of a rectangular 40 frame secured at its top to the frame A, and extending down to within a short distance of the floor. It is preferably formed of a size so 45 that its top will fit within said frame A, it being secured therein by screws or similar fastening devices, which pass through said top and into said frame. By this construction the top edge of said frame forms a convenient and suitable support for the bed D. The ends of said 50 frame are inclined from the top in toward the center of the lounge, and said ends being thus quite a distance from the ends of the lounge

are hidden from view. The front side of the frame is preferably hidden by a curtain, a, of fringe or other suitable material, tacked to the 55 front side of the lounge. The receptacle is thus completely hidden from view, and the appearance of the lounge not marred thereby. The bottom of said receptacle is preferably formed by tacking canvas or similar material, 60 C', to the cross-bars c, at the ends thereof, and c' in its center, but of course may be any suitable bottom for the purpose. The cross-bars c are placed a short distance from the lower 65 edge of the ends of the frame, and the end of the canvas being secured thereto an opening, c', is formed at each end of the receptacle, through which all dust and dirt which may 70 collect therein can be easily discharged. I thus provide a very handy receptacle in which 75 the bed-clothing can be placed during the day or while not in use.

The bed D is of any suitable construction, and is hinged to the front side of the frame of the section A by pivots, as shown, said pivots 75 being inserted through the ends of the bed-frame, near its corners, into the ends of the main frame. The corners of this edge of the bed are also rounded to prevent them from striking the frame or top of the receptacle on 80 which it rests when being turned on said pivots. A strap or handle, d, is provided on its opposite side, by which it is raised up when it is desired to gain access to the receptacle C for any purpose. When it is closed 85 down, it rests upon the top edge of said receptacle, which thus supports it in position, as before described.

The legs E are preferably mitered onto a longitudinal strip, E', which is hinged to the 90 side of the section B, but of course may be hinged to the side directly, if desired. Said strip E' is of sufficient length to bring the legs, which are secured to each end thereof, at the proper points, near the ends of the section B, 95 to properly support it. It is hinged to the side of the frame by the hinges E', one strap of which is bent to hook down over the edge of the side piece of the frame B, and is secured thereto by screws inserted both downwardly 100 through the horizontal part into the edge of said side piece, and also through the bent-down vertical part into the back side of said side piece, thereby providing a very secure

and durable connection. The other strap is secured to the strip E' in the usual manner, a space being left between the top edge of said strip and the hinge-joint equal to the thickness of the side piece of the frame B, thereby permitting said strip and the legs thereon to be folded entirely over into the bed out of the way when it is desired to fold up the lounge. Said strip E' and the legs are secured in position to support the section B by a jointed catch, e, which is secured to the side of said section, and the free end of which is adapted to be turned up and placed in engagement with a button, e', on the under edge of said strip, said catch and button being preferably so adjusted as to necessitate the springing in of the strip toward the side piece, in order to place the catch over the button, as it will then spring out and hold the legs rigidly.

20 The operation of my improved lounge is as follows: It being in the position shown in Fig. 1, and it being desired to open it for use as a bed, the hinged section B is opened out in the usual manner, and the strip E', having the 25 legs E thereon, is turned out down onto the outside of the frame, bringing the legs upon the floor in position to support the section, and is secured in this position by pressing the catch e up over the button e', as before described. The bed D is then raised up and the bed-clothing removed from the receptacle C under it for use.

The operation of changing from the bed to the lounge is of course simply the reverse. The 35 bed-clothing is removed, placed in the receptacle, the catch e disengaged from the button e', the legs turned up over into the bed, and the section B then closed down in the usual manner.

40 I am aware that receptacles have heretofore been formed under the bed of bed-lounges, and that said beds have been hinged to afford access to said receptacles; but I am not aware that the particular construction and arrangement herein set forth and claimed have ever been made.

Having thus fully described my said invention, what I claim as new, and desire to secure by Letters Patent, is—

50 1. The combination, in a bed-lounge, of the main section A, hinged section B, receptacle C, constructed to fit within the frame A at its

top and being secured therein, the bottom of said receptacle being formed of cross-slats and canvas secured thereon, the end slats being a 55 short distance from the end of the receptacle and the end of the canvas being secured thereto, thereby providing an opening, c², at each end for the discharge of dirt, &c., and a hinged bed, D, hinged at one side to the frame A and 60 resting upon the top edge of said receptacle C when in a closed down position, substantially as set forth.

2. The combination, in a bed-lounge, of the main section A, hinged section B, receptacle C, 65 secured to said frame A, hinged bed D, and legs E, secured to the strip E', said strip E' hinged to the frame B by the hinges E², a sufficient space being left between the top edge of said strip and the joint of the hinge to allow said strip to be turned entirely over into the bed, 70 substantially as described, and for the purposes specified.

3. The combination, in a bed-lounge, of the main section A, hinged section B, legs E, secured to the strip E', said strip E' hinged to the frame B by the hinges E², said hinge E², one strap of which is bent and thus adapted to fit onto two sides of the side piece and thereby permit screws to be inserted through 80 it in two directions, and the other of which is secured to the strip E' at a distance from the joint of said hinge sufficient to permit said strip to be turned entirely over the edge of the side piece into the bed, and means for securing said strip and legs in position to support the frame B, substantially as set forth. 85

4. The combination, with the hinged section of a bed-lounge, of hinged legs hinged to the outer side thereof, a space being left between the top of the leg or piece to which it is secured and the joint of the hinge sufficient to permit said legs to be turned up over the edge of the side piece to which it is hinged from a position supporting said section to a 90 position on or in the bed, substantially as set forth.

In witness whereof I have hereunto set my hand and seal, at Indianapolis, Indiana, this 13th day of March, A. D. 1885.

GEORGE E. KRAUSE. [L. S.]

In presence of—

E. W. BRADFORD,
CHARLES L. THURBER.
